COAL LADDER.

1,408,659.

Specification of Letters Patent. Patented Mar. 7, 1922.

Application filed December 3, 1920. Serial No. 428,081.

To all whom it may concern:

Be it known that we, WILLIS H. TOWNE, OTTO M. THJOMOE, and WILLIAM B. MERCER, citizens of the United States, residing at 5 Chicago, in the county of Cook and State of Illinois, have invented a new and useful Improvement in Coal Ladders, of which the following is a specification.

Our invention relates to an improved construction of coal ladder for use in coal silos, consisting in a broken helical slide or chute adapted for use on the inner cylindrical wall of the silo, particularly where the interior of the silo is divided into a plurality of bins 15 by vertical partitions extending radially of the silo.

We are aware that coal ladders have heretofore been proposed, consisting of a series of straight slides or chutes and also that it has 20 been proposed to use a spiral or helical slide or chute extending completely around the inner surface of a cylindrical silo to convey coal from the top of the silo to the bottom in filling the same. The coal ladder referred to 25 however, is not applicable for use in cylindrical silos and the continuous spiral or helical chute can not be used in cylindrical silos containing a plurality of bins. In practice it is advisable in many instances to divide 30 cylindrical silos into two or more bins extending from top to bottom of the silo, by vertical partitions from the center of the silo to the outer cylindrical wall of the same, in order that the silo may accommodate and 35 store two or more kinds of coal. In storing coal in silos of the kind under consideration, it is elevated by suitable means forming no part of the present invention, to the upper end of the silo and either dropped into the 40 silo or conveyed from the top thereof to the bottom by a slide construction arranged to conduct or convey the coal easily and without great speed to the bottom of the silo. In dropping the coal from the top of the silo 45 to the bottom a large amount of breakage occurs which materially reduces the value of the coal since coal silos of this kind are about fifty feet high. As far as we are aware, no practical slide construction has heretofore 50 been proposed adapted for use in a segmental bin of a cylindrical silo. It is an object of our present invention to provide a slide construction of helical conformation on the inner cylindrical wall of a segmental bin of 55 a cylindrical silo, said slide being in sections

in reverse relation to each other and arranged to transfer the coal from one section of said slide to another section adjacent to a partition between said bin and another segmental bin of the silo. It is a further object 60 of our invention to construct each section of the slide so that its surface will be inclined radially of the silo, as a result of which the centrifugal force of the coal moving down the slide will be partially or entirely balanced as desired by the inwardly directed radial component of the weight of the coal on the slide due to the inclination of the latter. By our invention we also provide a construction by which the surface of the 65 slide may be given a varying degree of radial inclination to accommodate and compensate for the centrifugal forces exerted upon coal of different kind and size as it passes down the slide. 70

Our invention will best be understood by reference to the accompanying drawings showing a preferred embodiment thereof in which—

Fig. 1 shows in vertical sectional view a 80 silo of cylindrical construction having two bins, the slide construction being shown in full lines,

Fig. 2 is a sectional view of the silo shown in Fig. 1, taken along the line 2—2, 85

Fig. 3 is an enlarged sectional view of the slide construction shown in Figs. 1 and 2 taken along the line 3—3 in Fig. 2, and

Fig. 4 shows in a view similar to Fig. 3 a modified construction of the slide such that 90 the inclination of the surface of the slide varies radially.

Similar numerals refer to similar parts throughout the several views.

As shown in the drawings, the silo consists of a cylindrical outer wall 10, preferably of concrete, wood, tile or steel, divided into separate bins A and B by a vertical partition 11 which extends across the silo from its top to its lower portion, which lower portion contains inclined walls or floors 12 and 13 constituting the bottoms of the bins A and B respectively and serving to deliver the contents of the bins to the loading chutes 14 and 15 when suitable controlling gates 16 100 and 17 are operated.

The coal to be stored in the silo is elevated by suitable means not shown, as it forms no part of our invention, which elevating means delivers the coal to a horizontal conveyer 18 110

provided with gates 19 and 20 for delivering the coal either to the bin B or the bin A as desired. The bin A has disposed in it a helical chute consisting of the sections 21 and 22, the upper end of the section 21 being extended to receive the coal delivered through the gate 20 and the lower end of said section being above the upper end of the section 22 and terminating at a sufficient distance from the partition 11 to permit the coal to pass from the section 21 to the section 22 without undue shock or jar. A retaining member 23 is preferably provided at the lower end of the section 21 and the upper end of the section 22 of a width and height to prevent the coal dropping laterally from the slide as it leaves the section 21 and begins its reversed downward motion on the section 22. The partition 23 extends to the partition 11 and should be made no wider or higher than required to accomplish the result indicated. The lower end of the section 22 terminates a sufficient distance from the partition 11 and a sufficient distance above the bottom 12 to permit the coal passing from said section to be delivered on the bottom 12 without undue shock or jar. The bin B is provided with a similar slide, only the upper section 24 of which is shown, it being understood that this slide is similar to that described for the bin A. The upper end of the section 24 is extended to receive coal delivered through the gate 19 from the conveyer 18. It will thus be seen that coal may be delivered either to the bin A or the bin B down the slide construction described, depending upon whether the gate 20 or 19 is opened.

Each of the slide sections is similarly constructed, this construction being shown in detail in Fig. 3 as follows: The slide itself consists preferably of a plurality of oak boards of about 3 or 4 inches in width and about 1 inch thick placed on edge and secured to each other so as to constitute a continuous surface on which the coal may slide. The slide thus constructed is supported by brackets 25 secured to the inner surface of the wall 10 of the silo, the upper edges of the brackets 25 and the upper and lower surfaces of the silo sections being preferably inclined downwards towards the center of the silo a sufficient amount so that as the coal slides down the slide sections, substantially counterbalanced forces will be exerted upon the coal as follows: In the first place the circular motion of the coal in its descent down the slide will produce a considerable centrifugal force upon it tending to move it outwardly against the inner surface of the wall 10; secondly the weight of the coal acting upon the radially inclined surface results in two force components, the first of which is exerted per-

section while the second of these components is exerted parallel to said surface radially and would tend to move the coal inwardly towards the center of the silo, were there no other force acting upon the coal; by 70 properly inclining the upper surface of the slide sections radially we find that we can substantially counterbalance the centrifugal force upon the coal by the second of the components mentioned and in this way insure that the coal will move freely down the slide without being crowded to its outer edge and therefore without rubbing and grinding the pieces of coal against each other and without forcing the coal against 80 the inner surface of the wall 10, thus materially reducing the breakage of coal which would otherwise occur. In practice we find a satisfactory radial inclination of the slide section to be about 1 unit in 85 height for 8 units in width for the slide sections although we do not limit ourselves to any particular radial inclination as long as substantially the results indicated, are secured. In any event it is not desirable that 90 the radial inclination of the slide sections be sufficient to cause any of the coal to drop from the inner edge of the slide to the bottom of the bin.

In practice we find that the longitudinal 95 inclination of the slide sections may be varied considerably depending upon the kind and size of coal to be handled by the slides and that for usual cases this inclination may be from 25 to 40 degrees with a 100 horizontal plane.

In practice we find satisfactory results are secured with a silo of about 50 feet in height and 18 feet inside diameter, divided into two bins substantially as shown, by the 105 use of two sections of slide although it will be apparent that other numbers of sections may be used for other sizes of silos or for the same size where other numbers of bins are provided in the silo, thus reducing the 110 amount of cylindrical wall available for the slide sections and we do not therefore limit ourselves in carrying out our invention, to any particular number of sections to constitute a complete slide from top to bottom of a 115 bin. It will readily appear that our invention above described is equally applicable to bins of other annular extent than 180 degrees of the outer wall of the silo and that all that is required in using our construction 120 in a bin of any particular extent angularly, is to use the number of slide sections required by the longitudinal inclination decided upon in that case, to reach from top to bottom of the bin.

In the construction shown in Fig. 4 the slide section 24^a is of substantially the same general construction and is supported in the same manner described above for the section 24, the only difference being that the 130

upper surface of the section 24^a is of varying radial inclination as a result of which the slide will properly handle different kinds and sizes of coal since the coal will move 5 outwardly on the slide radially until the balanced relation of the forces acting upon the coal above indicated is secured. This varying radial inclination is preferably secured by giving the upper surface of the 10 slide a curved conformation radially, the radius of curvature decreasing from the inner edge to the outer edge of the slide section.

A further advantage secured by our radially inclined slide is that after a bin has been 15 filled by use of the slide, and the coal has afterwards been removed from the bin, pieces of the coal will not readily remain on the slide but will move therefrom into 20 the bin, whereas if the slide were level radially, under the conditions just referred to, pieces of the coal would remain on the slide to be struck by the next coal passing down the slide in refilling the bin with the result 25 that considerable breakage would occur which is avoided by our present construction.

While we have shown our invention in the particular embodiment above described, 30 it will be understood that we do not limit ourselves to this exact construction as we may employ equivalents known to the art at the time of the filing of this application without departing from the scope of the 35 appended claims.

What we claim is:

1. In combination, a bin having vertical walls comprising cylindrical and flat inner surfaces, and a noncontinuous helical slide 40 mounted on said cylindrical surface, said slide consisting of a plurality of sections extending reversely down said cylindrical surface with the lower end of one of said sections above the upper end of a second one of 45 said sections, said lower end clearing said upper end and the flat inner surface of said bin, and said sections having upper surfaces on which material will slide helically towards the bottom of said bin, whereby said 50 material will flow from the lower end of said one section to the upper end of said second section and then in reversed direction down said second section.

2. In combination, a bin having vertical 55 walls comprising cylindrical and flat inner surfaces, a non-continuous helical slide mounted on said cylindrical surface, said slide consisting of a plurality of sections extending reversely down said cylindrical surface with the lower end of one of said sections above the upper end of a second one of 60 said sections, said lower end clearing said upper end and the flat inner surface of said bin, and said sections having upper surfaces 65 on which material will slide helically towards

the bottom of said bin, whereby said material will flow from the lower end of said one section to the upper end of said second section and then in reversed direction down said second section, and an inner vertical retaining member 70 at the upper end of said second section to prevent overflow of said material during its change in direction of motion.

3. In combination, a bin having vertical walls comprising cylindrical and flat inner 75 surfaces, and a non-continuous helical slide mounted on said cylindrical surface, said slide consisting of a plurality of sections extending reversely down said cylindrical surface with the lower end of one of said sections above the upper end of a second one of 80 said sections, said lower end clearing said upper end and the flat inner surface of said bin, and said sections having upper surfaces on which material will slide helically towards the bottom of said bin, whereby said material will flow from the lower end of said one section to the upper end of said second section and then in reversed direction down 85 said second section, the upper surface of 90 each of said sections being inclined downwards radially towards the axis of said cylindrical surface to substantially counteract the centrifugal force of material moving down said section.

4. In combination, a bin having vertical walls comprising cylindrical and flat inner surfaces, and a non-continuous helical slide mounted on said cylindrical surface, said slide consisting of a plurality of sections extending reversely down said cylindrical surface with the lower end of one of said sections above the upper end of a second one of 95 said sections, said lower end clearing said upper end and the flat inner surface of said bin, and said sections having upper surfaces on which material will slide helically towards the bottom of said bin, whereby said material will flow from the lower end of said one section to the upper end of said second section and then in reversed direction down 100 said second section, the upper surface of each of said sections being inclined downwards radially towards the axis of said cylindrical surface to substantially counteract the centrifugal force of material moving down said section, said radially inclination varying in amount radially across said upper surface, and being of less inclination to a horizontal plane at the inner edge of said surface than 105 at its outer edge.

5. In combination, a bin having vertical walls comprising cylindrical and flat inner surfaces, and a non-continuous helical slide mounted on said cylindrical surface, said 110 slide consisting of a plurality of sections extending reversely down said cylindrical surface with the lower end of one of said sections above the upper end of a second one of 115 said sections, said lower end clearing said upper end and the flat inner surface of said bin, and said sections having upper surfaces 120 on which material will slide helically towards

4
upper end and the flat inner surface of said bin and said sections having upper surfaces on which material will slide helically towards the bottom of said bin, whereby, said 5 material will flow from the lower end of said one section to the upper end of said second section and then in reversed direction down said second section, the upper surface of each of said sections being curved radially and having a greater inclination to a 10 vertical plane at the outer edge of said section than at its inner edge.

6. In combination, a coal silo having a cylindrical outer wall, vertical partitions extending from top to bottom of said silo from the central portion of said silo to its outer wall to divide said silo into bins, and a sectional helical slide mounted in each bin on the inner surface of said outer wall, said 15 slide consisting of a plurality of helical sections extending reversely down said inner surface, a first one of said sections ending adjacent a vertical partition and over the upper end of a second one of said sections 20 but separated from said partition and said upper end to permit material to pass freely from said first section to said second section.

7. In combination, a coal silo having a cylindrical outer wall, vertical partitions extending from top to bottom of said silo from the central portion of said silo to its outer wall to divide said silo into bins, and a sectional helical slide mounted in each bin on the inner surface of said outer wall, said 30 slide consisting of a plurality of helical sections extending reversely down said inner surface, a first one of said sections ending adjacent a vertical partition and over the upper end of a second one of said sections 35 but separated from said partition and said upper end to permit material to pass freely from said first section to said second section, the upper ends of the upper sections of said slides being disposed in different locations in 40 the upper end of the silo to facilitate delivering material to any bin as desired.

8. In combination, a coal silo having a cylindrical outer wall, vertical partitions extending from top to bottom of said silo from the central portion of said silo to its outer wall to divide said silo into bins, a sectional helical slide mounted in each bin on the inner surface of said outer wall, said slide 50 consisting of a plurality of helical sections 55 extending reversely down said inner surface, a first one of said sections ending adjacent a vertical partition and over the upper end of a second one of said sections but separated from said partition and said upper end to permit material to pass freely from said 60 first section to said second section, and an outwardly and downwardly inclined bottom for each bin adjacent the lower free end of the lowermost section of the slide in said bin

to receive material from said slide and facilitate removing it from said bin.

9. In combination, a coal silo having a cylindrical outer wall, vertical partitions extending from top to bottom of said silo from the central portion of said silo to its 70 outer wall to divide said silo into bins, a sectional helical slide mounted in each bin on the inner surface of said outer wall, said slide consisting of a plurality of helical sections extending reversely down said 75 inner surface, a first one of said sections ending adjacent a vertical partition and over the upper end of a second one of said sections but separated from said partition and said upper end to permit material to 80 pass freely from said first section to said second section, and a retaining member on the inner edge of the upper end of each lower section of said slides extending to the adjacent partition and upwards adjacent 85 the lower end of the section above said lower section.

10. In combination, a coal silo having a cylindrical outer wall, vertical partitions extending from top to bottom of said silo 90 from the central portion of said silo to its outer wall to divide said silo into bins, and a sectional helical slide mounted in each bin on the inner surface of said outer wall, said slide 95 consisting of a plurality of helical sections extending reversely down said inner surface, a first one of said sections ending adjacent a vertical partition and over the upper end of a second one of said sections but separated from said partition and said 100 upper end to permit material to pass freely from said first section to said second section, the upper surface of each of said sections being inclined downwards radially towards the axis of said silo.

11. In combination, a coal silo having a cylindrical outer wall, vertical partitions extending from top to bottom of said silo from the central portion of said silo to its outer wall to divide said silo into bins, and 110 a sectional helical slide mounted in each bin on the inner surface of said outer wall, said slide consisting of a plurality of helical sections 115 extending reversely down said inner surface, a first one of said sections ending adjacent a vertical partition and over the upper end of a second one of said sections but separated from said partition and said upper end to permit material to 120 pass freely from said first section to said second section, the upper surface of each of said sections being curved radially and upwardly from the inner edge to the outer edge of said section, the radius of said curvature progressively decreasing from the inner to 125 the outer edge of said section.

12. In a device of the class described, a broken helical slide comprising similar sec-

- tions reversely arranged over each other around a vertical axis with the lower end of a first section adjacent and separated from the upper end of a second section whereby material may pass from one section to the other and have its direction of downward motion reversed, devices for preventing lateral inward flow of material from the upper end of said second section, and a retaining member projecting upwardly from the outer edge of each section.
13. In a device of the class described, a broken helical slide comprising similar sections reversely arranged over each other around a vertical axis with the lower end of a first section adjacent and separated from the upper end of a second section whereby material may pass from one section to the other and have its direction of downward motion reversed, devices for preventing lateral inward flow of material from the upper end of said second section, and a retaining member projecting upwardly from the outer edge of each section, the upper surface of each of said sections being inclined downwards radially towards the axis of said slide.
14. In a device of the class described, a broken helical slide comprising similar sections reversely arranged over each other around a vertical axis with the lower end of a first section adjacent and separated from the upper end of a second section whereby material may pass from one sec-
- tion to the other and have its direction of downward motion reversed, devices for preventing lateral inward flow of material from the upper end of said second section, and a retaining member projecting upwardly from the outer edge of each section, the upper surface of each of said sections being curved radially and upwardly from the inner edge to the outer edge of said section.
15. In a device of the class described, the combination of a helical slide having an upper surface inclined downwards towards the axis of the slide, and a retaining portion projecting upwardly from the outer part of the said upper surface.
16. In a device of the class described, the combination of a silo having a cylindrical wall, and a helical slide mounted on the inner surface of said wall, said slide having an upper surface inclined downwards radially of the silo.
17. In a device of the class described, the combination of a bin having vertical walls comprising cylindrical and flat inner surfaces, and a helical slide on said cylindrical surface, said slide having an upper surface inclined downwards radially of said cylindrical surface.

In witness whereof, we hereunto subscribe our names this 23rd day of November, A. D. 1920.
